RELAY

Marvin Nelsen and Theodore Obaxarny, Chicago,
Ill., assignors to Guardian Electric Manufacturing
Company, Chicago, Ill., a corporation
of Illinois

Application April 5, 1939, Serial No. 266,118

4 Claims. (Cl. 200—87)

This invention relates to electro-magnetic relay devices of the type including a swingable armature hingedly supported at one end on a mounting bracket or field piece.

5 In most relay devices as heretofore designed and manufactured, the armature is fabricated totally of ferrous metal and is directly connected to the field piece, which tends to result in causing sticking or binding of the armature, and delaying its movement toward or away from the magnetic core. This condition is due to residual magnetism in the armature caused by its being in the path of the magnetic field currents. Moreover, such prior devices required substantial time 10 in proper adjustment during assembly due to the substantially fixed type pivot or hinge connection of the armature to the field piece.

The primary object of this invention is to provide a novel and improved form of relay device 20 which eliminates the foregoing difficulties.

Another and more specific object is to provide a novel armature construction, characterized by the provision of a section of non-ferrous metal at the locale of the hinged support on the field 25 piece, to eliminate direct contact of the ferrous metal portion of the armature with the field piece.

A further object is to provide a novel form 30 of flexible hinge support for the armature on the field piece which permits lateral rocking of the armature in a direction transversely of its hinge axis, to more readily facilitate proper aligning and seating of the armature on the end of the core.

35 Still another object is to provide a novel construction of field piece and armature by virtue of which one or more banks of switches may be conveniently mounted or replaced, for direct actuation by the movement of the armature.

40 A still further object of this invention is to provide an improved form of hinge support for the armature, by virtue of which a substantial saving of time is effected in proper adjustment 45 of the armature during initial assembly of the relay.

Other objects and advantages of the present invention will be apparent from the following description, taken in connection with the accompanying drawing, in which:

Fig. 1 is a view in side elevation of the relay embodying our present invention.

Fig. 2 is a top plan view of the relay device.

Fig. 3 is an end view of the relay device.

Fig. 4 is an enlarged, fragmentary, end view

of the field piece, showing the novel form of hinged support for the armature.

Fig. 5 is an enlarged, transverse, sectional view taken as indicated at line 5—5 on Fig. 4.

The electro-magnetic relay structure comprising the present invention and illustrated in the drawing, includes a field piece or bracket member 10 having a foot 11 and an upstanding leg 12, the upper end of which is bent laterally and rearwardly to form a shelf 13 to which may be secured one or more banks of switch units as hereinafter described. Mounted in upright position on the foot portion 11 of the field piece is a conventional coil 14, disposed adjacent the leg 12, and having a core 15, the coil being fully insulated from the foot piece 11 by a sheet of insulating material 16. The relay device herein illustrated is intended for use with A. C. current and to avoid hum and chatter, which is a common occurrence in most types of small A. C. relays heretofore manufactured, we employ a relatively large copper shading ring 17, rigidly attached to the end of the core 15 protruding above said coil 14. The ends of the wire of the coil 14 are soldered to terminal clips 18, to which may be conveniently attached or soldered conductor wires for connection of the coil in an electrical circuit.

Mounted for cooperation with the protruding upper end of the core 15 is an armature 20, which 30 is adapted to be hingedly and flexibly supported on the leg 12 of the field bracket for rocking movement in two transverse directions relatively to said leg. The armature proper is made of ferrous metal so as to permit magnetic attraction 35 to the core, and the end of said armature adjacent the leg 12 of the field bracket is upwardly offset as indicated in the drawing, and is rigidly attached by means of rivets 21 to a mounting plate or extension 22 of non-ferrous material, 40 such as brass, which extends through an elongated aperture or slot 12^a formed in the leg of the field piece. Said mounting plate together with the portion of the bracket surrounding said aperture 12^a are formed with interlocking tongue 45 and groove features as indicated at 12^b and 22^b, respectively, which permit of only a slight amount of lateral movement of the armature and mounting plate with respect to the field piece 10, as may be seen in Figs. 4 and 5. This construction, 50 however, is such as to afford adequate vertical movement of the armature toward and away from the end of the core 15. The bottom edge of the slot 12^a, upon which the mounting plate 22 of the armature is supported, is arcuately rounded 55

as indicated at 12^c so that in addition to providing a hinged support about which the armature is free to swing vertically, toward and away from the core 15, it also permits a slight amount 5 of lateral rocking movement of the armature in a direction transversely of the hinge axis to facilitate aligning and proper seating of the armature on the core 15 and to assure more perfect seating and engagement of the armature on the end 10 of said core, as may be seen in Figs. 4 and 5. Obviously, if desired, this rocking effect may also be produced by imposing a convex curvature on the under surface of the mounting plate 22 in registration with a flat surface constituting the bottom 15 of the slot 12^a in the leg 12 of the field piece.

By virtue of this construction, the work required to properly adjust the armature with respect to the core, during process of assembling a relay device, is reduced to only a fraction of that 20 heretofore required in the assembly and adjustment of similar type relay devices. Furthermore, by reason of the fact that the mounting plate 22 of the armature is of non-ferrous metal, and due to its support and mounting as above described, 25 the total armature structure in effect is what is termed a "full floating" flexible armature mounting, and prevents residual magnetism in the armature, and eliminates friction and binding or sticking at the hinge support for the armature 30 by the elimination of the effect of said residual magnetism.

The armature is normally maintained in the position seen in Fig. 1 of the drawing out of engagement with the core 15, by a coil spring 23 35 connected to the outer end of the mounting plate 22 and to a lug 12^c stamped out of the lower end of the leg portion 12 of the field piece 10. The armature is limited in its swinging upward movement away from the core 15 by a stop in the form 40 of a finger 25, which is a part of a stamped element 26, rigidly secured to the shelf extension 13 of the field piece. Said finger and bracket are also formed of non-ferrous metal to break the path of magnetic currents and thereby eliminate 45 any effect on the armature by the stray magnetic currents set up in the field piece. Said bracket is provided with a pair of spaced-apart downturned fingers 28^b terminating a short distance above the armature, adjacent its hinge connection 50 to limit the amount of vertical movement of said end of the armature, and to hold it locked against endwise displacement by engagement of the tongue and groove features 12^b and 22^b.

The outer end of the armature proper is formed 55 with an upturned leg 20^b to which is secured by rivets 27 an upstanding lifter bar or panel 28 of insulating material, the upper end of which is provided with one or more horizontally disposed, elongated slots 29. Mounted on the shelf portion 60 13 of the field piece, with the bracket 26 interposed and, as shown in the drawing, is a switch element adapted to be controlled by the actuation of the armature and includes a plurality of blocks 65 of insulating material, indicated at 30, and a pair 31 of spring bar type conductor fingers 31 and 32 provided with cooperating contact buttons 31^a and 32^a, respectively; and, as seen in the drawing, said finger 32 is longer than finger 31 and projects through the elongated slot 29 in the insulating panel 28. When the armature 20 is in 70 the position seen in Fig. 1, the panel 28 of insulating material is in elevated position and at which position said spring finger 32 and its contact button 32^a is held away from contact button 75 31^a of finger 31. The insulating panel 28, by

reason of its shape and position, also serves to protect the switch fingers against injury. Obviously, when the armature 20 is attracted to the core 15, the panel 28, due to its direct connection to the armature, is also drawn downwardly and thereby yieldingly moves finger 32 to cause its contact button 32^a to move into wiping engagement with cooperating contact button 31^a to complete a portion of an electric circuit including the switch. The ends of conductor fingers 31 and 32 10 project rearwardly beyond the blocks 30 of insulating material and provide terminals 31^b and 32^b to which may be connected, such as by soldering, conductor wires of an electrical circuit to be controlled by said switch. When more than one 15 switch of the character indicated is mounted on shelf extension 13, one finger of each switch is formed with an extension, at its free end, projecting into a slot in panel 28, so as to cause raising or lowering of said extended finger, incident to 20 actuation of said armature, for making and breaking contact between cooperating switch fingers of said switches.

Although we have herein shown and described a preferred embodiment of our invention, manifestly it is capable of modification and rearrangement of parts without departing from the spirit and scope thereof. We do not, therefore, wish to be understood as limiting this invention to the precise embodiment herein disclosed, except as it 30 may be so limited by the appended claims.

We claim:

1. In an electro-magnetic relay including a coil and a core; the combination of a field piece of ferrous metal having an upright leg disposed adjacent the coil, an armature hingedly mounted at one end on said upright leg of the field piece and including a main body portion of ferrous metal located in registration with the end of the core, an extension piece of non-magnetic material 35 rigidly attached to said main body portion and directly connected to the upright leg of the field piece for hingedly supporting said main ferrous body portion of the armature out of direct contact with the field piece, and a member of non-magnetic material secured to said leg of the field piece and having an extension located above said main body portion of the armature in position to be engaged by said armature for limiting its movement away from the core. 50

2. In an electro-magnetic relay including a coil and a core; the combination of a field piece of ferrous metal having an upright leg disposed adjacent the coil, and an armature hingedly and flexibly mounted at one end on said upright leg 55 of the field piece and including a main body portion of ferrous metal located in registration with the end of the core, an extension piece of non-magnetic material rigidly attached to said main body portion and projecting through and 60 loosely mounted in an elongated slot formed in said leg for hingedly supporting said main ferrous body portion of the armature out of direct contact with the field piece, the lower surface defining said slot in the leg including an arcuate 65 portion to permit lateral rocking of the armature in a direction transversely of its hinged movement toward and away from said core and a member of non-magnetic material secured to said leg of the field piece and having an extension located above said main body portion of the armature in position to be engaged by said armature for limiting its movement away from the core. 70

3. In an electro-magnetic relay including a 75

- coil and a core; the combination of a field piece having an upright leg of ferrous metal disposed adjacent the coil, an armature hingedly and flexibly mounted at one end on said upright leg of the field piece, located in registration with the end of the core, the upper end of said leg, above said armature, being bent rearwardly away from the coil to form a shelf, a member of non-magnetic material mounted on said shelf and having an extension located above said armature in position to be engaged by said armature for limiting its movement away from the core, a switch including a pair of cooperating yieldable conductor fingers extending over and out of range of movement of said armature and secured to said shelf with said member interposed therebetween, and a member of insulating material rigidly mounted on the armature adjacent its free end, one finger of said switch being longer than the other and having its end disposed in position to be engaged by the insulating member for controlling the make-and-break of said fingers incident to the movement of said armature.
4. In an electro-magnetic relay including a coil and a core; the combination of a field piece of ferrous metal having an upright leg disposed adjacent the coil, a shelf portion extending rearwardly from the upper end of said leg, an armature hingedly and flexibly mounted at one end on said upright leg of the field piece and located in registration with the end of the core, a member of non-magnetic material mounted on said shelf and having an extension located above said armature in position to be engaged by said armature for limiting its movement away from the core, a switch including a pair of cooperating yieldable conductor fingers extending over and out of range of movement of said armature and secured to said shelf with said member interposed therebetween, and a member of insulating material mounted on the armature adjacent its free end, one finger of said switch being longer than the other and having its end disposed in position to be engaged by the insulating member for controlling the make-and-break of said fingers incident to the movement of said armature.
